(57) **CLAIM**

The ornamental design for an electronic portable device, as shown and described.

DESCRIPTION

FIG. 1 is a perspective view showing the front and bottom edge of the device.

FIG. 2 is a front view of the device.

FIG. 3 is a rear view of the device.

FIG. 4 is a bottom view of the device.

FIG. 5 is a side view of the device; opposing left and right side views of the device are the same; and,

FIG. 6 is a top view of the device.

The design comprises an electronic portable device. The device has a display panel, preferably for use in providing travel and traffic information to a user. The device is preferably removably mountable in a vehicle. The module may comprise location determining means, e.g. a global navigation satellite system (GNSS) receiver.
